UNITED STATES PATENT OFFICE

2,508,461

APPARATUS FOR PRACTICING PING-PONG
AND THE LIKE

George Lemon, Youngstown, Ohio

Application November 5, 1946, Serial No. 707,782

2 Claims. (Cl. 273—30)

1

This invention relates to exercising and amusement devices and more particularly to improved apparatus for automatically aiding in the playing of table tennis or ping-pong games and the like. The primary object of the invention is the provision of a simple and inexpensive assembly which may be employed as a silent or robot partner in the playing of table tennis and the like or which may be utilized as a practicing device to enable a single individual to improve his playing of table tennis and analogous games.

A further object of the invention is the provision of improved and simplified apparatus of the general character above specified which is readily portable in nature so that it may be quickly and easily associated with or disassociated from the conventional table tennis equipment as desired. For this purpose the apparatus is constructed of light-weight materials, is of minimum dimension, and has its own inherent supporting features so that it may be independently supported whether associated with or disassociated from the conventional table surface.

A still further object of the invention is the provision of improved apparatus for the purpose stated and having the characteristics above enumerated which utilizes for its motive or driving power a conventional piece of household equipment as a tank-type vacuum cleaner, for example. In this manner the apparatus while entirely automatic in its operation and quick in its response may yet be produced in a most economical manner.

The above and other objects and advantages of the invention will become apparent upon consideration of the following detailed specification and the accompanying drawing wherein there is disclosed a preferred embodiment of the invention.

In the drawing:

Figure 1 is a perspective view of an assembled device constructed in accordance with the principles of the invention;

Figure 2 is a fragmentary transverse section of the apparatus of Figure 1; and

Figure 3 is a fragmentary longitudinal section through the apparatus of Figure 1.

In Figure 1 there is shown, in dotted outline, a conventional table for playing table tennis and as such this table has an extended flat surface 10 across which is stretched the vertically disposed net 11. As is well understood this equipment is normally employed by two or four players, one or two of whom position themselves adjacent each end of the table. The apparatus of

2

this invention is adapted to be positioned closely adjacent one end of the table and is operative to return back onto the table and in a direction toward the opposite end thereof balls which have been previously served by a player standing at said opposite end of the table.

For accomplishing the above object I provide a back stop or screen 12 having a width substantially equal to the width of the table top 10, of a height operative to intercept the greater portion of the balls served on the contiguous half of the table top 10 from the opposite end of the table, and being of a pliant nature so that the intercepted balls will not tend to re-bound back onto the table but, rather, will tend to fall vertically down the front face of the screen. As shown, the screen 12 is stretched between two vertical parallel frame members 13 and 14 and a cross bar 15 interconnects the upper ends of the frame members 13 and 14.

Frame members 13 and 14 are of a length to position the lower edge of the screen 12 substantially in horizontal alignment with the table top 10. Positioned immediately below the screen 12 and partially received between the members 13 and 14 is an open-topped box structure having a rear wall 16, a front wall 17, end walls 18, and a bottom wall 19 which slopes downwardly toward the center portion of the box structure. The bottom wall 19 is provided with a depending sump 20 through which projects a tube 21 having an opening 22 in the upper portion of its surface. As shown, tube 21 projects outwardly of either side of the box structure and the opening 22 is slightly larger in diameter than the diameter of the table tennis or "ping-pong" balls which will be used with the assembly. Likewise, the diameter of the tube 21 is only slightly larger than the diameter of these balls.

Secured to the forward edge of the end walls 18 of the box structure above described and depending downwardly therefrom is a pair of leg members 23 which together with the lower portions of the frame members 13 and 14 provide a four-legged stand or support for the apparatus

of the invention and it should be readily understood that the apparatus will stand on the floor independent of the table 10 when positioned either adjacent to or away from the table.

Coupled with the rear or discharge end of the tube 21 is a conduit 24 which curves upwardly and rearwardly to bring its discharge end into alignment with the front portion of the table top 10. Conduit 24 is preferably a length of flexible

hose in order that its position may be readily

varied and to support the upper or discharge end portion of a conduit 24 I may attach to the conduit a sling 25 which is entrained over the bar 15; and I may further provide a pair of diverging guide wires or strings 26 which have their upper ends attached to a discharge end portion of the conduit 24 while their lower ends are detachably coupled with the table 10. Of course, various other expedients may be employed to retain and guide the discharge end portion of the conduit 24 in adjusted position and therefore the illustrated embodiment should be considered as exemplary only. The internal diameter of the conduit 24 is also only slightly larger than the diameter of the balls which will be used with the apparatus.

In the apparatus above described air pressure applied to the inlet end of tube 21 is utilized to propel the successive playing balls up through the conduit 24 and out through the upper or discharge end thereof. This air pressure may conveniently be supplied by a tank-type of vacuum cleaner, shown in dotted outline at 27 in Figure 1, to the discharge or pressure side of which is attached a flexible hose 28 which in turn is connected to the inlet end of tube 21. In operation, with air being supplied through the hose 28, any ball which falls into the box structure formed by the walls 16-19 will immediately be swept up through and out of the conduit 24 upon its rolling down into the opening 22. Any suitable guiding means as, for example, the illustrated downwardly inclined portions of the tube 21, may be employed to facilitate the quick dropping of the ball or balls into the tube 21 through the opening 22.

It should now be apparent that I have provided improved apparatus in the nature of an exercising and amusement device which accomplishes the objects initially set out. The apparatus may be most economically constructed by making the screen 12 of soft inexpensive cloth, the frame members 13, 14, 15 and 23 of wood while the box structure above described may conveniently be fabricated of thin wood or paper product sheets as will be understood. The apparatus is readily portable and as such may readily be associated with any particular tennis table or removed therefrom as desired.

The above specifically described embodiment

of the invention should be considered as illustrative only as obviously many changes may be made therein without departing from the spirit or scope of the invention. Reference should therefore be had to the appended claims in determining the scope of the invention.

What I claim is:

1. Apparatus of the character described comprising in combination a pair of spaced parallel but vertically extending frame members and a horizontal bar spanning the upper ends of said frame members, a pliant screen spanning said frame members below said bar, an open-topped box positioned immediately in front of but below said screen and having a sloping bottom wall, a conduit passing through the lowermost portion of said box and curving upwardly and rearwardly and having its upper or discharge end portion contiguous to said bar and directed toward a position in front of said screen, said conduit having an opening in its side wall in said box to receive by gravity balls in succession from said box, and means adjustably supporting the discharge end portion of said conduit on said bar, the opposite or inlet end of said conduit being adapted to be connected with an air pressure supplying conduit.
2. Apparatus according to claim 1 further characterized in that said box is partially received in and is attached to said frame members intermediate their top and bottom ends, and downwardly extending supporting means attached to the forward edge portion of said box and being of a length substantially equal to the lengths of the portions of said frame members extending below said box whereby said apparatus may be independently supported on a floor and the like.

GEORGE LEMON.
